RETAINING WALL

Bertram H. Hirsch, 4949 Paradise Drive,
Tiburon, Calif. 94920

Filed Oct. 20, 1971, Ser. No. 191,145

Term of patent 14 years

Int. Cl. D25—02

U.S. Cl. D13—1 H

FIG_1

FIG_2

FIG_3

FIG_4

FIG_6

FIG_5

FIG_7

FIG_8

FIG. 1 is a front fragmentary perspective view of a retaining wall embodying the present invention showing the right-hand side of the wall which is a mirror image of the left-hand side of the wall;

FIG. 2 is a top elevation thereof;

FIG. 3 is a front plan view thereof;

FIG. 4 is a side elevation view thereof;

FIG. 5 is a front fragmentary perspective view of a modified form of the retaining wall illustrated in FIG. 1 showing the right-hand side of the wall which is a mirror image of the left-hand side of the wall;

FIG. 6 is a side elevation view thereof;

FIG. 7 is a front fragmentary perspective view of another modified form of the retaining wall illustrated in FIG. 1 showing the right-hand side of the wall which is a mirror image of the left-hand side of the wall; and

FIG. 8 is a side elevation view thereof.

I claim:

The ornamental design for a retaining wall, substantially as shown and described.
